(57) **CLAIM**

The ornamental design for a pontoon guard, as shown and described.

DESCRIPTION

FIG. 1 is a front perspective view of a first embodiment of a pontoon guard showing my new design;

FIG. 2 is a left elevation view of the pontoon guard shown in FIG. 1;

FIG. 3 is a right elevation view of the pontoon guard shown in FIG. 1;

FIG. 4 is a front elevation view of the pontoon guard shown in FIG. 1;

FIG. 5 is a rear elevation view of the pontoon guard shown in FIG. 1;

FIG. 6 is a top plan view of the pontoon guard shown in FIG. 1;

FIG. 7 is a bottom plan view of the pontoon guard shown in FIG. 1;

FIG. 8 is a reduced perspective view of the pontoon guard as shown in FIG. 1 applied to a portion of an outer surface of a pontoon;

FIG. 9 is a front perspective view of a second embodiment of a pontoon guard showing my new design having a reflective center strip along the outer surface;

FIG. 10 is a left elevation view of the pontoon guard shown in FIG. 9;

FIG. 11 is a right elevation view of the pontoon guard shown in FIG. 9;

FIG. 12 is a front elevation view of the pontoon guard shown in FIG. 9;

FIG. 13 is a rear elevation view of the pontoon guard shown in FIG. 9;

FIG. 14 is a top plan view of the pontoon guard shown in FIG. 9;

FIG. 15 is a bottom plan view of the pontoon guard shown in FIG. 9; and,

FIG. 16 is a reduced perspective view of the pontoon guard as shown in FIG. 9 applied to a portion of an outer surface of a pontoon.

FIGS. 1-3, 6, 7, 9-11, 14 & 15 are shown separated for ease and clarity of illustration.

The broken lines in FIGS. 8 & 16 represent the environment in which the article resides and forms no part of the claimed design.

1 Claim, 10 Drawing Sheets
